United States Patent Office.

A. H. BLAISDELL, OF NEWTON CORNERS, MASSACHUSETTS.

Letters Patent No. 79,052, dated June 23, 1868.

IMPROVEMENT IN CARPENTERS' GAUGES.

The Schedule referred to in these Letters Patent and making part of the same.

TO ALL WHOM IT MAY CONCERN:

Be it known that I, A. H. BLAISDELL, of Newton Corners, in the county of Middlesex, and State of Massachusetts, have invented a new and improved Carpenters' Gauge; and I do hereby declare that the following is a full, clear, and exact description thereof, which will enable others skilled in the art to make and use the same, reference being had to the accompanying drawings, forming part of this specification.

Figures 1, 2, and 3 represent inverted plan views of my improved carpenters' gauge.

Figure 4 is a longitudinal section of the same, taken on the plane of the line $x x$, fig. 1.

Similar letters of reference indicate corresponding parts.

This invention relates to a new carpenters' gauge for drawing marks parallel to the straight or curved edge of a board or other article, and the invention consists in the use of V-shaped links or fingers, pivoted to a sliding block, said links being by means of rods connected with a beam, that is pivoted to another fixed but adjustable block.

The ends of these fingers form the edge of the gauge, and they will, when the gauge is drawn along the curved edge of a board, always adjust themselves, by swinging around their pivot-pins, so as to keep the marking-point the required distance from the board's edge.

A, in the drawing, represents the bar or rod of a carpenters' gauge. Near one end of the same is formed thereon a marking-point, a , as shown.

B is a block sliding on A; it can be clamped thereon by means of a set-screw, b , as shown.

C is another block, sliding on the rod A, between the point a and the slide B. A rod, D, projects from the block C towards and through the block B, and can be clamped by means of a set-screw, c , fitted in B as shown, so that if B is clamped by means of the screw b , C can also be clamped by means of the screw c . On the under face of the block C are pivoted two V-shaped fingers, E E, by means of pins d , as shown, the inner ends of these fingers being, by means of rods e , connected with the ends of a bar, f , that is at its middle pivoted by means of a pin, g , to the block B, as shown.

When the device is to be used as a gauge for straight-edged boards, as in fig. 3, the block C had better be clamped by means of the screw c , and can then be used on either side, as on the upper side of the rod A, marking-pins, $h h$, are secured, as shown.

When used on curved edges, as in figs. 1 and 2, the block C should be left free to slide, while B is fixed. The four ends of the two fingers E will always be in contact with the edge of the board, and will thereby insure that the rod is held at right angles to the edge, and as they turn on their pivots, with their inner ends forward, on concave edges, they will cause the block C to slide backwards, and with their outer ends forward on convex curves, they will cause the block C to move forward, and as they are previously properly adjusted, they will in this manner always keep the point a the required distance from the edge.

To set the block C at the required distance from the point a , the screw b is turned so as to release the block B, when the two blocks, B and C, are by one movement adjusted nearer to or farther from the said point a , and clamped by means of the screw b .

I claim as new, and desire to secure by Letters Patent—

The fingers E E, pivoted on the sliding block C, and operating so that their four ends will always remain in contact with a curved or straight edge, substantially as herein shown and described.

A. H. BLAISDELL.
